PAPER CLIP

Harry G. Pasholian, Worcester, Mass.

Application July 13, 1935, Serial No. 31,216

4 Claims. (Cl. 24—261)

This invention relates to paper clips of the type commonly used to secure two or more sheets of paper together or to attach small pieces of paper, coupons, checks and the like to larger sheets, such as letter heads.

One object of the invention is to provide a device of this character which may be readily constructed from wire or the like, and which is capable of being applied to paper sheets with equal readiness from any point throughout the circumference of the clip, and which may be placed in considerable number loosely within a container without becoming entangled with each other so as to require careful separation before being used.

Another object of the invention is the provision of a clip of this character which is so constructed as to prevent, in ordinary usage, the roughened ends from coming into sole contact with one side of the paper, which frequently results in tearing a portion from one of the papers attached together with clips of the ordinary construction when the clip is removed.

Other objects and advantages of the invention relate to various novel details of construction and arrangement of the parts as will be more fully set forth in the detailed description to follow.

Referring to the drawing:

Fig. 1 is a plan view of one form of the invention.

Fig. 2 is an assembled view, showing the clip in one of its attached positions as applied to two strips of paper to hold them in connected relation.

Figs. 3 and 4 are views similar to Fig. 2, illustrating the position of the parts when the paper clip is applied to associated paper sheets from different angular positions throughout its circumference, and,

Fig. 5 is a plan view of a slightly modified form of paper clip.

In devices of this character as previously made, the clip is given an oblong shape or provided with outwardly projecting spaced ribs for guiding the clip in its attachment to two or more superposed paper sheets. This necessitates the application of the clip from a certain definite angle and requires that the clip be turned into that position before it can be applied properly.

Furthermore, in many such clips the paper must be inserted so that one of the free ends of the wire is the sole engaging means contacting the paper at one point and clamps tightly against one face of one of the paper sheets. Since the wire ends are roughened in cutting, these rough-

ened ends frequently tear the paper of one or more sheets when they are removed from the paper, unless the removal is effected with great care.

In that form of the invention shown in Figs. 1 to 4 of the drawing, the clip is preferably formed from a resilient metal wire 1 arranged in the form of a flat spiral and having a plurality of convolutions 2, certain or all of which convolutions may be spaced somewhat from each other as indicated at 3 for a purpose which will be more fully described hereinafter. The inner end 4 of the wire is bent outwardly as shown into close

contact with the inner surface of the adjacent convolution, and the outer end 5 of the wire is bent inwardly into close contact with the outer surface of the adjacent convolution. The points of contact between the inner end 4 and the outer end 5 of the wire with the surface of adjacent convolutions may be located at or adjacent to a common radius 6 in order that greater facility may be provided for the application of the clip without forcing the paper between one free end of the wire and its adjacent convolution so as to cause a free end of the wire to bear directly upon one surface of the paper without having the support of the adjacent convolution to prevent tearing of the paper in the removal of the clip.

As will be seen upon reference to Figs. 2, 3 and 4 of the drawing, the clip is adapted to be applied to the paper sheets or pieces 7 from substantially any angle throughout its circumference, and in such a manner as to avoid the insertion of the paper sheets between one free end portion of the wire and the remaining portions of the clip.

The free ends 4 and 5 of the wire are preferably bent into close engagement with the adjoining surface of adjacent convolutions, which when taken in connection with the fact that certain of the convolutions at least are spaced from each other radially a material distance, as indicated at 3, serves to permit the clip to be applied most naturally and readily by inserting the paper between adjacent convolutions rather than between a partial convolution terminating in one end portion and the remaining convolutions. This may be seen upon reference to Figs. 2, 3 and 4 of the drawing, wherein as in Fig. 2, one entire convolution of the spiral is located upon one side of the sheet, and the remaining convolutions on the other; or in Fig. 3, wherein substantially two convolutions are located upon one side of the sheet, and the remaining convolutions on the other; or as in Fig. 4, wherein between one and two convolutions are located outwardly of the

paper sheets, and the remaining convolutions upon the rearward side thereof.

Such a construction and arrangement of the parts wherein at least certain of the convolutions are spaced from each other radially, also renders

5 the clip more ready of application to a paper sheet or sheets, in that it is convenient in picking up the clip to place the thumb or one finger at the center of the spiral while supporting the outer portion from the other side, and by the application of a slight pressure forcing the center out of the plane of the outer convolution and thus provide an opening between complete convolutions for the insertion of the papers to be held.

10 15 In that form of the invention shown in Fig. 5 of the drawing the clip may be formed from any suitable material, such as a resilient wire 8, and is in the form of a flat spiral, as in the embodiment previously described. The clip is provided

20 with an inner end portion 9 which may be bent to extend diametrically of or at any suitable angle relative to the circumference, and its free end portion 10 may contact with or be separated slightly from that part of the inner convolution

25 next adjacent thereto. In this form of the invention, as well as in that previously described, all parts of the clip are located substantially within a common plane. The outer free end portion 12 of the clip is bent inwardly into close engagement with the adjacent surface of the next convolution for the reasons more particularly set forth in connection with the forms shown in

30 Figs. 1 to 4 of the drawing. In the structure shown in Fig. 5, as in those previously described, 35 at least two of the adjacent convolutions 12 and 14 are spaced from each other a sufficient distance, as indicated by 15, to permit the ready insertion of paper sheets between the main portions of these convolutions without bringing one

40 side of the sheet or any part thereof into position where it will be clampingly engaged by a free end portion and thus render it liable to injury in the application or removal of the clip.

45 While in the form shown in the drawing, each convolution is spaced materially from the one next adjacent thereto throughout substantially its complete circumference, the manner of spacing the various convolutions from each other may be varied as may be found desirable, one complete convolution, at least, being spaced from the one next adjacent thereto throughout substan-

tially its entire extent to permit freedom of movement therebetween at right angles to the plane of the spiral.

What I claim is:—

1. A paper clip consisting of a spirally wound 5 resilient wire all parts of which are located substantially within a common plane and provided with free end portions located inwardly and outwardly of the spiral convolutions respectively, the outer of said end portions being bent inwardly 10 out of the curve of the spiral into close engagement with the adjacent portion of the outer convolution.

2. A paper clip formed of a resilient wire arranged with all parts lying substantially in a 15 common plane and in the form of a flat spiral, the free end portions of said wire being located respectively outwardly of and inwardly with relation to the several convolutions, and each of said end portions being bent somewhat out of the 20 normal path of the spiral and into close engagement with a portion of the next adjacent convolution.

3. A paper clip comprising a single piece of resilient wire bent into the form of a flat spiral 25 and having certain of the adjacent convolutions spaced from each other radially to permit substantially free movement of the central convolutions independently of the outer convolutions and having one free end of said wire closely engaging 30 that portion of the adjacent convolution which is in substantial opposition therewith radially of the clip.

4. A paper clip comprising a single piece of resilient wire curved throughout the major portion 35 of its extent to form a flat spiral in which certain of the adjacent convolutions are spaced from each other throughout their circumferential extents a sufficient distance to be capable of relative movement at right angles to the plane 40 of the spiral without frictional engagement with each other and having the outer free end portion thereof frictionally engaging that surface of the next adjacent convolution normally located in proximity thereto to facilitate the insertion of 45 paper sheets between the spaced convolutions and to tend to prevent the insertion of such sheets between the outer free end portion of the wire and the adjacent convolution.
